UNITED STATES PATENT OFFICE.

ALFRED WREAKS BOORAEM AND FREDERICK TROWBRIDGE HOWARD, OF BROOKLYN, NEW YORK.

ILLUSION APPARATUS.

SPECIFICATION forming part of Letters Patent No. 715,959, dated December 16, 1902.

Application filed June 24, 1902. Serial No. 113,043. (No model.)

To all whom it may concern:

Be it known that we, ALFRED WREAKS BOORAEM and FREDERICK TROWBRIDGE HOWARD, citizens of the United States, and 5 residents of the city of New York, borough of Brooklyn, in the county of Kings and State of New York, have invented new and useful Improvements in Illusion Apparatus, of which the following is a full, clear, and ex-10 act description.

Our invention relates to the class of sporting devices known as "illusion apparatus."

The object of our invention is more particularly to produce illusions in the minds of 15 passengers riding upon a sporting-way, such as a pleasure-railway or a pleasure-canal.

Reference is to be had to the accompanying drawings, forming a part of this specification, in which similar characters of reference indicate corresponding parts in all the figures. 20

Figure 1 is a horizontal section showing our invention as applied to a pleasure-railway. Fig. 2 is a vertical section upon the line $\alpha\alpha$ of Fig. 1. Fig. 3 is a fragmentary 25 elevation upon the line 33 of Fig. 1 looking in the direction of the arrow and showing the screen-frames upon which certain scenery is painted. Fig. 4 is a view somewhat similar to Fig. 3, but showing the scenery 30 painted upon the frame; and Fig. 5 is a fragmentary view somewhat similar to Fig. 1, but showing certain stationary screens replaced by movable screens.

The railroad-track 1 is provided with a sharp curve 2 and with a return-way 3, this latter element being of the kind already in use. Movable screens 4 5 are mounted upon rollers 6 7 8 9. Adjacent to the roller 6 and screen 4 is a large mirror 11, which abuts the 35 curved wall 10, as indicated in Fig. 1. This curved wall may be painted to represent scenery of any kind. A pair of walls or frames 12 13 are disposed at an angle toward each other and converge practically to a 40 point at 15. A pair of rails 14 are disposed in the position indicated in Fig. 1 so as to abut the mirror 11 and to converge practically at the point 15. The outer edges of the 45 frames 12 13 terminate in angles 16 17, these angles being the junction-lines between the frames 12 13 and the walls 18, which walls

may, if desired, be caused to represent scenery. The inner opposite faces of the frames 12 13 are painted or otherwise caused to represent scenery of any desired kind—such, for 55 instance, as is indicated in Fig. 4. When a passenger-car is upon the track 1 at the right hand of Fig. 1, the passengers thereon looking to the left in the direction of the mirror 11 will see a false perspective consisting of 60 the rails 14 and the scenery shown in Fig. 4. This false perspective has the appearance to these passengers of the continuation of the railroad, which to their eyes seems to be straight. Of course the scenery upon the 65 screens 12 13 may be varied at pleasure and may, if desired, represent a building or analogous structure, so as to give the passengers the impression that the car is about to crash into the same. The variety of scenery which 70 may be represented in this way is limited only by the skill of the artist.

The rollers 6 7 8 9 are actuated in any preferred manner—for instance, by the gear-wheel 25 or the belt 27. (Shown more particularly in Fig. 2.)

Instead of the stationary frames 12 13 movable aprons or screens 19 20, (see Fig. 5,) mounted upon rollers 21 22 23 24, may be employed. These aprons may of course be painted 80 so as to represent any kind of scenery. Preferably the scenery shown upon the movable aprons 19 20 should harmonize with that shown upon the aprons 4 5, so as to prevent any abruptness in the continuity of the scenery, 85 or at least to render the break as nearly imperceptible as possible.

A roof 26 may be provided immediately over the railroad, if desired, for the purpose of receiving the representation of the sky or 90 other overhead scenery.

The operation of our device is as follows: When the scenery of the kind indicated in Figs. 1, 2, and 4 is used, the screens or aprons 4 5 are given a rapid motion and the car travels along the track 1 toward the left. The car may travel very slowly, yet as the screen or aprons 4 5 are moved rapidly in a direction opposite that in which the car is traveling the passengers receive the illusory impression 95 that they are traveling at a tremendous rate of speed. If the motion of the car is somewhat

jerky or irregular, the illusion is rendered more realistic. The passengers looking ahead into the mirror see, as they suppose, in the distance a straight track. The distance, in fact, may represent several miles. If the stationary screens 12 13 are used, the scenery does not seem to move, because of its great distance, whereas if the movable screens 19 20 are used the motion of the scenery is attributed to excessive speed. This corresponds with the sensation of the passengers upon any railway while moving rapidly through the country. Looking a long way ahead the scenery in the vicinity of the track appears to be practically stationary, whereas the scenery immediately at hand appears to be moving rapidly toward the rear of the train. If, however, the aprons or screens 19 20 are used, motion is given to them by rollers 22 23 24. As above stated, all of the screens move in the direction indicated by the arrows in Fig. 5. Passengers looking ahead into the mirror see, as they suppose, a continuation of the track extending ahead for several miles in a straight line, the car apparently making progress relatively to each part of the scenery upon each side of the track. When the car reaches the curve and turns abruptly to the left, the scene changes instantly, so that the passengers are treated with a surprise. When the movable screens or aprons 19 20 are used, the scenery upon them should be as harmonious as possible to that upon the aprons 4 5. We do not limit ourselves to the use of screens placed vertically. They may be placed in any other relation. Having thus described our invention, we claim as new and desire to secure by Letters Patent—

1. An illusion apparatus, comprising a railway, a passenger-car for traveling upon the same, movable screens disposed upon oppo-

site sides of said railway and provided with scenery representing a perspective as viewed from said car, and means for actuating said car and said screen in opposite directions. 45

2. An illusion apparatus, comprising a way, a passenger-vehicle movable relatively thereto, screens movable relatively to said way and to said vehicle, and a false perspective so disposed relatively to said screens as to present to passengers upon said vehicle a practically-uninterrupted scene. 50

3. An illusion apparatus, comprising a way, a passenger-vehicle movable relatively thereto, a mirror disposed adjacent to said way, and a false perspective disposed adjacent to said mirror and reflected therefrom so as to be visible from said passenger-vehicle. 60

4. An illusion apparatus comprising a way provided with a curve, a vehicle for traveling upon said way, a mirror disposed adjacent to said curve, and a false perspective disposed adjacent to said mirror and said way, said false perspective being visible from said vehicle by reflection in said mirror, but otherwise invisible. 65

5. An illusion apparatus comprising a way provided with a curve, a mirror mounted adjacent to said curve, a plurality of movable screens mounted adjacent to said way and provided with scenery, a plurality of movable screens mounted adjacent to said mirror and provided with scenery, said scenery being visible from said way by reflection in said mirror, and a passenger-vehicle for traveling upon said way. 70

In testimony whereof we have signed our names to this specification in the presence of two subscribing witnesses. 75
